(57) **CLAIM**

I claim the ornamental design for a rear head for automobiles, as shown and described.

DESCRIPTION

FIG. 1 is a front perspective view of a rear head for automobiles showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof;

FIG. 7 is a bottom perspective view thereof; and,

FIG. 8 is a rear perspective view thereof.

The details shown in broken lines form no part of the claimed design.
